UNITED STATES PATENT OFFICE.

LOUIS G. WAGNER, OF ALAMEDA, CALIFORNIA.

PROTECTIVE CAP.

1,364,662.

Specification of Letters Patent.

Patented Jan. 4, 1921.

Application filed April 23, 1919. Serial No. 292,200.

To all whom it may concern:

Be it known that I, LOUIS G. WAGNER, a citizen of the United States, residing at Alameda, in the county of Alameda and State of California, have invented certain new and useful Improvements in Protective Caps, of which the following is a specification.

My invention is a protective cap for protecting the wearer from falling objects, such as red hot rivets, which often fall from iron structures while being built.

My invention is illustrated in the accompanying drawing which forms a part of this specification and the appended claims.

Referring to the drawing:

Figure 1 is a perspective view of my cap.

Fig. 2 is a perspective view of the skull cap over which fits the crown of the cap.

Fig. 3 is a longitudinal vertical section of the cap.

Fig. 4 is a sectional view of the rear shield of the cap.

In the drawing 1 indicates a skull cap 25 or lining, which includes a sweat band 2, a longitudinal band 3 secured at its ends to the front and rear of said sweat band, a transverse band 4 secured at its ends to the sides of said band and a shade 5 depending 30 from the lower front edge of the sweat band. A crown 6 fits over the skull cap 1, the lower edge thereof coinciding with the lower edge of the sweat band and is suitably secured thereto, as for example, by rivets 7 clenched 35 in the sweat band 1. The crown is preferably made of light, strong, non-fragile, non-combustible, heat and electrical insulating fibrous material.

The cap has a detachable shield 10, for 40 protecting the back of the head and neck of the wearer. Said shield is preferably made in a plurality of overlapping sections 11, 12 and 13 which are connected together by cords 14 near their upper edges so that 45 they may telescope or collapse to allow the wearer of the cap to bend his head backward. Hooks 15 secured to the forward upper ends of the shield section 11 engage 50 holes 16 in the sweat band and crown of the hat and detachably secure the rear shield to the cap. The crown may, if desirable, be covered with cloth, leather or other material 17.

The bands 3 and 4 of the skull cap engage 55 the top of the wearer's head and hold the top of the crown above the head.

In case a red hot rivet or other object should fall on the crown 6, it would bounce off and the pressure thereof would be distributed equally on the wearer's head by the 60 skull cap, thus preventing injury to the crown or the wearer of the cap. If the crown should engage a live electric wire it would protect the wearer against electric shock. The cap fits snug on the wearer's 65 head so that he could lie on his back or work in any position without the hat tipping or blowing off. The cap is as light as an ordinary working hat and is neat in appearance. The cap will wear much longer 70 than an ordinary hat. It may be scrubbed or washed with soap and kept clean. Being a non-conductor of heat and non-combustible it affords protection from the sun and is cool and affords protection against fire. 75

Having described my invention, I claim:

1. A protective cap of the character described, comprising a head receiving frame consisting of a sweat band and crossed strips of resilient material having their ends secured to said sweat band, and a superposed protective crown member of rigid material having its edge portion contacting with and immovably secured to said sweat band, the portion of said crown above said sweat band 80 being spaced from said frame.

2. A protective cap of the character described, comprising a head receiving frame consisting of a sweat band and crossed strips of resilient material having their ends secured to said sweat band, and a superposed protective crown member of rigid material having its edges immovably secured to said sweat band, the portion of said crown above said sweat band being spaced from said frame, a neck shield formed of a plurality of overlapping loosely connected plates detachably connected to said sweat band, and a vizor secured to the sweat band. 90

3. A protective cap of the character described, comprising a head receiving skull frame of resilient material including a sweat band, and a non-combustible and electric insulating substantially rigid crown overlying said frame and having its edge conforming 100 to the contour of the sweat band and secured thereto.

In testimony whereof I affix my signature.

LOUIS G. WAGNER.
